UNITED STATES PATENT OFFICE.

RAYMOND S. DALTON, OF CLEVELAND, OHIO, ASSIGNOR TO THE CLEVELAND FOLDING MACHINE COMPANY, OF CLEVELAND, OHIO, A CORPORATION OF OHIO.

FOLDING MACHINE.

Application filed December 20, 1926. Serial No. 155,839.

This invention relates to feeding rolls for paper handling machines and especially to feeding rolls for use in paper folding machines.

5 Heretofore it has been customary to use fluted or nurled rolls in which the grooves and ridges in the surface of the rolls were parallel to the axes. One example of such construction is shown in the Campbell Patent No. 1,589,584, granted June 22, 1926.

10 It is one of the objects of the present invention to provide an improved form of nurled feeding rolls that will be adapted to positively grip the sheets of paper at spaced 15 points throughout the length of the rolls so as to avoid any possibility of creasing or soiling the paper, and to insure accurate alignment of the sheets.

15 It is a further object of the invention to provide an improved form of feeding rolls that will accomplish the above stated objects without being more costly to manufacture.

20 Other objects of the invention and the features of novelty will be apparent from the following description, taken in connection with the accompanying drawings, of which:

25 Fig. 1 is an elevation of a pair of feeding rolls embodying my invention;

30 Fig. 2 is a transverse section thereof on the line 2-2 of Fig. 1; and

35 Fig. 3 is a diagram illustrating the principles of my invention.

Referring to the drawings, 10 and 11 indicate a pair of feeding rolls and, for clearness, the space 12, is exaggerated, it being understood that this space will be restricted 40 in accordance with the thickness of the sheet, whether folded or unfolded. The rolls 10 and 11 are provided with flutes or nurls which extend spirally, as shown at 13, and these flutes or nurls may be formed according to the method described in the aforesaid Patent No. 1,589,584, or otherwise as desired.

45 The angle of the flutes or nurls 13 is variable and, in practice, I have found that a spiral which advances circumferentially of the roll about $\frac{3}{8}$ of an inch in a length of 50 36 inches gives satisfactory results. The direction of the spirals is immaterial, that is they may be either right-hand or left-hand spirals, but I prefer to make the spirals

of both rolls alike. In other words, I prefer to make the spirals of both rolls either right-hand or left-hand so that, on the meeting or cooperating sides of the rolls, the flutes or nurls will extend at relatively opposite angles to the plane of the roll axes and thus cross or intersect, as illustrated in Fig. 3.

55 Fig. 3 may be considered as an exaggerated development, diagrammatically, of the flutes or nurls at the space 12, the flutes or nurls of the roll 10 being indicated by the full lines 14 and those of the roll 11 being indicated by the broken lines 15. The plane 60 of the roll axes is indicated at 16 and it will be noted that certain of the lines 14 and 15 intersect at the points 17. As the rolls revolve, assuming that the movement is in the direction of the arrow in Fig. 3, other intersections, such as indicated at 18, will come 65 into the plane 16. As the paper is passing between the rolls, it will be positively gripped at the points of intersection which are in the plane 16, but the nurling is, in 70 practice, made so fine that there will, at all times, be intersecting points at which the paper is gripped.

75 Having thus described my invention, what I claim is:

1. In paper feeding apparatus, a pair of 80 cooperating feed rolls having nurled surfaces on which the nurling is arranged in similar spirals so that the sheets of paper will be positively gripped by the cooperating 85 sides of the rolls at points which are spaced axially of the rolls.

2. In paper feeding apparatus, a pair of 90 cooperating feed rolls having nurled surfaces on which the nurling is arranged so that the sheets of paper will be positively gripped at any time at a plurality of points spaced axially of the rolls.

3. In paper feeding apparatus, a pair of 95 cooperating feed rolls having spirally nurled surfaces so that the cooperating sides of the rolls will positively grip the sheets of paper at any instant at spaced points.

In testimony whereof, I hereunto affix my signature.

RAYMOND S. DALTON.
